UNITED STATES PATENT OFFICE.

WILLIAM C. BUHLES, OF ALAMEDA, CALIFORNIA, ASSIGNOR TO ALUMINUM SEAL COMPANY, OF PITTSBURGH, PENNSYLVANIA, A CORPORATION OF PENNSYLVANIA.

PACKING AND THE METHOD OF MAKING THE SAME.

1,162,026.

Specification of Letters Patent. Patented Nov. 30, 1915.

Application filed April 28, 1915. Serial No. 24,558.

To all whom it may concern:

Be it known that I, WILLIAM C. BUHLES, a citizen of the United States, and a resident of Alameda, county of Alameda, and 5 State of California, have invented a new and useful Packing and the Method of Making the Same, of which the following is a specification.

The invention relates to a waterproof 10 packing for sealing joints or closing receptacles, and particularly to a packing for placing in caps or closures for receptacles adapted to contain liquid.

An object of the invention is to provide 15 a waterproof packing.

A further object of the invention is to provide a method of manufacturing waterproof packing.

The invention possesses other objects and 20 advantageous features, some of which, with the foregoing, will be set forth at length in the following description, where I shall outline in full that form of the invention and the method of manufacture, which I have 25 selected for illustration in the drawings accompanying and forming part of the present specification. In the drawings I have shown only one specific form of my invention, but it is to be understood that I do not limit 30 myself to such form, because my invention may be embodied in a multiplicity of forms, each being a species of my said invention. It is also to be understood that by the claims 35 succeeding the description, I desire to cover the invention in whatever form it may be embodied.

In the drawings I have shown one form of the packing and the apparatus used for making it.

40 Figures 1, 2 and 3 show portions of the dies and three successive stages of the operation of forming a packing disk. Fig. 4 is a plan view of a packing disk of my invention. Fig. 5 is a section of the packing 45 disk taken on the line A—A Fig. 4.

I have shown the invention herein as embodied in a packing disk, but the shape of the packing is immaterial. The disk packing, however, is the most widely used and 50 is, therefore, the preferred form to illustrate. Packing disks are principally used in caps or closures for receptacles to seal the joint between the upper edge of the receptacle and the cap. The body of the packing 55 ing so used consists generally of a disk of

material capable of being pressed into conformance with the mouth of the bottle or receptacle, and is usually composed of fibrous material such as cork or paper. The packing is provided on its lower surface, or 60 that surface which contacts with the bottle, with a thin sheet of impervious waterproof material, to prevent the liquid from soaking into and through the fibrous disk and to prevent the passage of air or gas into or 65 out of the receptacle through the somewhat porous fibrous material. In accordance with my invention the sheet of impervious material is pressed or stamped into locking engagement with the fibrous sheet, producing 70 a new packing, and the locking of the two sheets is preferably performed in the same operation with the cutting of the disk or other shaped packing from sheets of material. This operation is preferably performed by means of a die and I shall describe a die capable of performing the operation of making packing disks in accordance with my invention. The sheet 2 of 75 fibrous material with an overlying sheet 3 80 of this impervious material, such as waterproof paper, is placed on the female die 4, which, when a disk is to be cut, is annular in shape. Arranged above the female die and concentric therewith, is a reciprocating 85 male die 5, having an external diameter substantially equal to the internal diameter of the female die. The male die is provided on its lower surface at the periphery with a plurality of projections 6, spaced 90 apart circumferentially. The outer surfaces 7 of the projections are flush with the side of the die and the under surfaces 8 are inclined upward from the lower edge of the projection to the body of the die. The side 95 faces of each projection preferably digress from each other outwardly, so that they form an outwardly flaring or dove-tailed cut. The lower face of the die at the periphery is preferably sloped upward 100 slightly between the projections.

As the male die is brought down on the superposed sheets, a plurality of circumferentially disposed dove-tailed tongues 12 105 are cut in the sheet 3 of impervious material, and pressed into flaring depressions formed in the fibrous sheet 2, and then the further movement of the die cuts the disk 13 from the sheets. The disk is formed of a relatively thick layer of fibrous or con- 110

formable material and a superposed layer of thin impervious material having a plurality of circumferentially disposed tongues pressed into depressions 14 in the thick layer. 5 By forming the tongues dove-tailed in shape, the thin impervious layer is locked to the thick fibrous layer against radial displacement and by pressing tongues of the thin layer into the thick layer and parts, are 10 held together against axial displacement. I, therefore, provide a packing disk having an impervious surface and cut the disk from the sheet and attach the two layers in one operation and without the use of any adhesive. 15

I claim:

1. An article of manufacture, comprising a piece of fibrous material and a piece of impervious material in interlocked engagement whereby said pieces are held together. 20
2. An article of manufacture, comprising a piece of fibrous material, and a piece of impervious material having a plurality of tongues seated in depressions in the fibrous material. 25
3. An article of manufacture, comprising a disk of conformable material having a plurality of circumferentially disposed depressions therein and a disk of impervious material having a plurality of circumferentially disposed tongues seated in said depressions. 30

4. An article of manufacture, comprising a disk of fibrous material having a plurality of circumferentially disposed outwardly flaring depressions therein and a disk of thin impervious material having a plurality of circumferentially disposed outwardly flaring tongues seated in said depressions. 35

5. An article of manufacture comprising a piece of relatively thick material and a superposed piece of relatively thin material interlocking therewith whereby said materials are held together. 40

6. The method of making the herein-described article of manufacture which consists in superposing two sheets of material and simultaneously cutting pieces from said sheets and pressing said pieces into locking engagement. 45

7. The method of making a packing disk which consists in superposing a sheet of impervious material on a sheet of fibrous material, cutting a plurality of circumferential tongues on said sheet of impervious material and pressing them into locked engagement with the sheet of fibrous material and cutting the locked disks from the sheets. 50

In testimony whereof, I have hereunto set my hand at San Francisco, California, 60 this 22d day of April 1915.

WILLIAM C. BUHLES.

In presence of—
H. G. PROST.
